2033

UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S TEA-GOWN.

SPECIFICATION forming part of Design No. 18,255, dated April 10, 1888.

Application filed February 23, 1888. Serial No. 265,054. Term of patent 3½ years.

To all whom it may concern:

Be it known that I, JENNIE SHEILS, of the city, county, and State of New York, have invented and produced a new and original Design for a Pattern of a Lady's Tea-Gown; and I do hereby declare that the engraved prints accompanying this specification convey to any one accustomed to using paper patterns a clear understanding of how a garment made up by the pattern will appear.

The design shows long fronts folding back in narrow lapels at their front edges to a little below the waist-line and flaring below the lapels over a fan-plaited skirt; a full vest drooping over the top of a plaited skirt and displaying a fullness at the neck; a close-fitting back with

an undersfolded triple box-plait below its center seams and undersfolded side plaits below the waist-line of the side back seams, and displays a short oval train; patch pockets with fancy turn-down laps on the hip; a standing collar, and bell sleeves folding upward at their wrists.

What I claim as my invention, and desire to secure by Letters Patent, is—

The design for a lady's tea-gown, as shown in the engraved prints accompanying this specification.

JENNIE SHEILS.
